Application March 21, 1939, Serial No. 263,277
In Germany March 21, 1938

9 Claims. (Cl. 179—18)

The present invention relates to a circuit arrangement for remote signalling or telephone installations in which finder switches have access to high or low valued junction lines. In such systems it is desired that impulses outgoing from high valued junction lines shall have finder switches at their disposal without any appreciable delay.

In previously known arrangements with high and low valued junction lines the situation could arise that when an impulse was transmitted from a high value junction line at a particular moment to the finder switch directly after it had been impelled from a low valued junction line then the high valued junction would have to wait until the discharge of the low valued call before the finder switch was placed at its disposal.

In the present invention such long waiting periods are avoided. This is arranged by preparing the finder switches over two starting chains arranged one behind the other separated according to the group to which the junction lines belong of which the chain for the high valued call is stepped on independently of the stopping of a finder switch impelled over the chain for the low valued call as soon as the impelled finder switch has overrun the contact positions provided for the high valued junction line while the chain for the low valued calling impulse is stepped on immediately on receipt of an impulse over the chain for the high valued impulse.

By this arrangement it is possible to impulse a second finder switch on receipt of an impulse from a high valued junction line while a finder switch impulse by a low valued connection is operating. In this way the original finder switch impelled from the lower valued connection takes up the impulse transmitted from the high valued set and starts up the second finder switch over the series connection transferring the low valued impulse. Each of these two finder switches can connect the high valued junction line and the finder switch still operating can discharge the low valued connection.

Further by the arrangement according to the invention the further stepping on of the chain for high valued calls is possible previous to the switching through of a finder switch in operation impelled over the low valued chain in that in those cases in which a finder switch impelled by a low valued impulse has overrun the contact positions provided for the high valued connections another finder switch is prepared for the

higher valued impulse previous to the stopping of the first operated finder switch.

In the drawing an embodiment of the invention is shown to which however the invention is not limited.

10 A subscriber of a high valued junction line is indicated by T_h and a subscriber of a low valued junction line by T_n . As many finder switches, such as AS_1 and AS_2 , are provided for the discharge of calls as may be necessary. These switches are identical, and, as will be seen, are connected in multiple to the subscriber's lines so that each has access to all of said lines; they are also connected in series by two impulse circuits, whereby they may be rendered operative in turn, as will now be described. The impulse circuit for the high valued junction lines is indicated by A_h while the impulse circuit for the low valued call impulse is indicated by A_n . If the subscriber of the set T_n makes a call the relay R_2 is energized in the following circuit: earth, contact $25t_2$, the loop of the subscriber T_n , contact $24t_2$, winding I of relay R_2 , battery, earth. The relay R_2 operates the contacts $21r_2$, 15 and $22r_2$. By means of contact $21r_2$ the calling subscriber's set is marked in the contact bank of each of the finder switches. Contact $22r_2$ sets up the following impulse circuit over the circuit A_n : earth, contact $22r_2$, $23t_2$, distributor V_n , contact $16t_3$, $4u_3$, relay R_3 , battery, earth. The relay R_3 energizes and operates its contacts. Over contact $8r_3$ the test circuit for the finder switch AS_1 is prepared. The contact $7r_3$ sets 20 up the following stepping on circuit for the rotary magnet Das : earth, interrupter U_n , contact $7r_3$, wiper d in its zero position, contact $13p_3$ rotary magnet Das , battery, earth. The interrupter U_n connects the rotary magnet whereupon the stepping on circuit is maintained over the wiper d independently of contact $7r_3$ until the relay P_3 is energized over the line characterized by the contact $21r_2$. The following circuit is completed when the finder switch AS_1 rests on the calling line: earth, battery, winding 25 II of relay R_2 , relay T_2 , contact $21r_2$, wiper c , windings I and II of relay P_3 , contact $8r_3$, earth. In this circuit the relays P_3 and T_2 operate. Relay R_2 is maintained energized over the winding II. The contacts $10p_3$ and $11p_3$ switch through the talking conductors. The contact $14p_3$ connects relay T_3 to the outgoing conductor L_c whereupon relay T_3 operates over a battery not shown. Relay T_3 closes contact $15t_3$ over which the circuit for the relay P_3 is maintained after the closing of contact $12p_3$. The

stopping of the finder switch takes place on the openings of 13p3. At contact 16t3 the starting circuit An is stepped on to the next finder switch AS2. On the operation of the relay T2 the contacts 25t2 and 24t2 are operated so that the calling set is connected with the devices beyond the finder switch AS1 over the lines La—Lb. By means of contact 23t2 the impulse to the impulse circuit An is interrupted. The relay R3 restores and opens contacts 7r3 and 8r3.

When the party at the subscriber's set Tn hangs up his receiver the switching means not shown on the conductors La and Lb restore. In this way the circuit for the relay T3 is interrupted at the conductor Lc. The relay T3 restores and over contact 16t3 again makes the finder switch AS1 seizable by connection of the relay R3. The relay P3 restores and over the contact 13p3 closes the stepping on circuit for the contact 23t2 the impulse is disconnected from the impulse line An. The further setting up of connections over finder switch AS2 takes place in the same manner as has been described in the setting of the finder switch AS1.

When the finder switch AS1 has stepped on over the contact positions provided for the high valued lines during its search for a low valued call, the starting chain Ah is switched on to the next finder switch at the wiper e. Thereafter a high valued call impulse can be transferred directly to finder switch AS2 when the contacts provided for the high valued junction lines have been passed over by switch AS1 without the hunting finder switch AS1 having to switch through the circuit at contact 17t3 by energizing of relay T3.

If the finder switch AS1 is impelled by means of a low valued junction line over the impulse circuit An, for example from the subscriber of the subscriber's line Tn, the following impulse circuit is completed by a high valued subscriber calling at this moment (e. g. Th): earth, contact 2r1, 20t1, distributor Vh, wiper e of the finder switch AS1 which is hunting, contact 17t3, windings II and I of relay U3, battery, earth. In this circuit relay U3 energizes and operates its contacts. By means of contact 6u3 the winding I of relay U3 is short-circuited so that it now acts as a slow relay. The contact 3u3 sets up a holding circuit for the relay R3 energized over the impulse circuit An. The contact 5u3 maintains the preparation of the test circuit for the relay P3 of the finder switch AS1. The contact 4u3 connects the starting circuit for the low valued impulse on to finder switch AS2 which is reached over the line Ln. Relay R3 in this finder switch now operates owing to the impulse existing for contact 22r2 and therefore starts finder switch AS2 in exactly the same fashion as described above for AS1, so that two finder switches are hunting simultaneously.

It will now be assumed that the original finder switch AS1 set into operation by the low valued impulse has reached the calling line of a subscriber Th earlier than the finder switch AS2 impelled by the operating of contact 4u3. In this case the following circuit is completed for the relays P3 and T1: earth, contact 5u3, or 8r3, the relays P3 and T1: earth, contact 5u3, or 8r3, windings II and I of relay P3, wiper c, contact 1r1, relay T1, winding II of relay R1, battery, earth. In this circuit the relays P3 and T1 operate. The relay P3 by opening contact 13p3 stops the rotary magnet Das. The relay T1 operates the contacts 18t1 and 19t1 so that the subscriber Th is connected with the line La, subscriber Th is connected with the line La, Lb. The contact 1r1 is maintained closed since Lb. The contact 1r1 is maintained energized over the relay R1 is maintained energized over the

winding II. The contact 20t1 is opened so that the relay U3 begins to restore. In the meanwhile however the relay T3 is energized over contact 14p3 so that the release of the relay U3 at the opening of contact 4u3 does not bring about the switching over to the chain for the low valued connection since the contact 16t3 maintains the switching over. The contact 17t3 switches over the circuit for high valued impulses so that other calling impulses present on the multiple connection Vh are transmitted over line Lh to subsequently arranged finder switches.

The finder switch AS2 impelled over the starting circuit An is stepped on until it has found the line marked by the closing of contact 21r2. When this takes place the relay T2 is energized in series with P3'. The latter relay halts the switch AS2 by opening contact 13p3', and at contact 23t2 the impulse is disconnected from the impulse line An. The further setting up of connections over finder switch AS2 takes place in the same manner as has been described in the setting of the finder switch AS1.

What is claimed is:

1. In a telephone system, subscribers' lines, finder switches adapted to search for and seize calling ones of said lines, means at times controlled by the initiation of calls from two of said lines in rapid succession for starting a first switch to search for one of the calling lines and starting a second switch to search for the other of the calling lines even before said first switch has found said one line, said means at other times controlled by the initiation of calls from two of said lines in rapid succession for starting a first switch to search for one of the calling lines and then starting a second switch to search for the other of the calling lines only responsive to said first switch finding said one line.

2. In a telephone system, lines of different classes, finder switches having access to said lines, means for operating one of said switches to cause it to search for a calling one of said lines, and means controlled by the initiation of a call from another of said lines while said operated switch is still searching for said one line for initiating the operation of another of said switches either before or after said one switch finds said one line depending upon the class of said one line.

3. In a telephone system, lines of different classes, finder switches having access to said lines, means for operating one of said switches to cause it to search for a calling one of said lines, and means controlled by the initiation of a call from another of said lines while said operated switch is still searching for said one line for initiating the operation of another of said switches either before or after said one switch finds said one line depending upon the class of said other line.

4. In a telephone system, lines of different classes, finder switches having access to said lines, means for operating one of said switches to cause it to search for a calling one of said lines, and means controlled by the initiation of a call from another of said lines while said operated switch is still searching for said one line for initiating the operation of another of said switches either responsive to said one switch finding said one line or independently of said one switch finding said one line, depending upon the class of said one line.

5. In a telephone system, lines of different classes, finder switches having access to said

lines, means for operating one of said switches to cause it to search for a calling one of said lines, and means controlled by the initiation of a call from another of said lines while said operated switch is still searching for said one line for initiating the operation of another of said switches either responsive to said one switch finding said one line or independently of said one switch finding said one line, depending upon the class of said other line.

6. In a telephone system, lines of different classes, finder switches having access to said lines, means for operating one of said switches to cause it to search for a calling one of said lines, means controlled by the initiation of a call from another of said lines while said one switch is still searching for said one line for initiating the operation of another of said switches responsive to said one switch finding said one line if said one line and said other line are of the same class, and means controlled by the initiation of a call from another of said lines while said one switch is still hunting for said one line for initiating the operation of another of said switches independently of said one switch finding said one line if said one line and said other line are of different classes.

7. In a telephone system, two groups of lines, finder switches having access to said lines, a finder start circuit common to the lines of one group, a second finder start circuit common to the lines of the second group, means responsive to a call from any line for applying potential to

- the start circuit common to the group of which the calling line is one, means thereupon operated over said start circuit by said potential to start one of said switches to search for said calling line, means for transferring one of said start circuits to another switch while said one switch is still searching for the calling line, thereby to condition said other switch to operate before said one switch finds said calling line in the event a subsequent call is originated in one group of lines while said one switch is still searching, and means for transferring the other of said start circuits to said other switch only responsive to said one switch finding said calling line, thereby to prevent said other switch from operating before said one switch finds said calling line in the event a subsequent call is originated in the other group of lines while said one switch is still searching.
8. A telephone system as claimed in claim 7, wherein the start circuit transferred to said other switch while said one switch is still searching extends over a wiper of said one switch.
9. In a telephone system, a plurality of subscribers' lines, a plurality of finder switches having access to said lines, and means operated over a wiper of one of said switches responsive to one of said lines initiating a call for at times starting said one switch to search for the calling line and at other times starting another of said switches to search for the calling line, whereby a connection from a calling one of said lines may be completed over either of said switches.

WILHELM SCHELLER.
